Primary Examiner — Cathron C Brooks*(74) Attorney, Agent, or Firm* — Tucker Ellis LLP(57) CLAIM

The ornamental design for a bed, as shown and described.

DESCRIPTION

FIG. 1 is a front-right-top perspective view of a bed showing my new design;

FIG. 2 is front view thereof;

FIG. 3 is a rear view thereof;

FIG. 4 is a left side view thereof;

FIG. 5 is a right side view thereof;

FIG. 6 is a top view thereof, shown in reduced scale; and,

FIG. 7 is a bottom view thereof.

The broken lines illustrate portions of the bed that form no part of the claimed design.
